Primary Examiner—Doris V. Coles*Assistant Examiner*—Catherine R. Oliver
Attorney, Agent, or Firm—Frank Cozzarelli, Jr.[57] **CLAIM**

The ornamental design for a hose trough for tank truck, as shown.

DESCRIPTION

FIG. 1 is a front perspective view of the hose trough for tank truck of the present invention;

FIG. 2 is a front perspective view of the hose trough for tank truck of the present invention;

FIG. 3 is a plan view of the hose trough for tank truck of the present invention;

FIG. 4 is a front view in elevation of the hose trough for tank truck of the present invention;

FIG. 5 is a bottom view of the hose trough for tank truck of the present invention;

FIG. 6 is a left end view in elevation of the hose trough for tank truck of the present invention; and,

FIG. 7 is a right end view in elevation of the hose trough for tank truck of the present invention.

The broken line showing of environment in FIGS. 1,2, and 4 is for illustrative purposes only and forms no part of the claimed design.
